UNITED STATES PATENT OFFICE.

GEORGE A. JACOBS, OF CHICAGO, ILLINOIS.

WINDSHIELD HINGE.

Application filed February 6, 1924. Serial No. 691,030.

This invention relates to a hinge or pivot for automobile windshields, door transoms and the like, wherein it is desirable to swing the glass frame open to varying extents and to retain it in such a position to prevent accidental closure.

It is an object of this invention to provide an improved windshield hinge having automatic self-locking means acting at the periphery of a disc, whereby both the fineness of adjustment and the leverage of the locking means are increased.

It is also an object of this invention to provide a compact, self-contained pivot hinge that can be mounted in a narrow space between the glass frame and the support with only the attaching lugs projecting over the inner surface of the frame and support.

It is a further object of this invention to provide a compact structure that eliminates thick castings by the use of sheet metal stamping so formed as to entirely enclose the operating parts of the mechanism.

Other and further important objects of this invention will be apparent from the disclosures in the specification and the accompanying drawings.

The invention (in a preferred form) is illustrated in the drawings and hereinafter more fully described.

On the drawings:

Figure 1 is a view of one side of a device embodying the features of this invention.

Figure 2 is a corresponding view of the other side.

Figure 3 is a corresponding edge view of the device looking down on Figures 1 and 2.

Figure 4 is a section on the line 4—4 of Figure 3.

Figure 5 is a section on the line 5—5 of Figure 3, showing the device attached between a windshield and its bracket or support.

As shown on the drawings:

A disc is indicated by the reference numeral 10 having a flanged rim 11 with a series of outwardly projecting semi-spherical indentations 12 formed therein. The disc is preferably a metal stamping, and fastening lugs 13 and a central pivot recess 14 can be struck therefrom during the process of manufacture. A smaller disc 15 fits within

the rim 11 of the disc 10 and has a central pivot recess 16 aligned with the recess 14, a countersunk head bolt 17 forming a pivot between the sections. It will be noted that Figure 5 shows that the recesses or depressions 14 and 16 abut, and so serve to properly space the discs 10 and 15. Similar fastening lugs 13 are struck from the inner disc 15 and are fastened to the frame of the movable object such as the windshield frame or sash 18, shown in Figure 5.

Oppositely disposed lugs 19 are struck inwardly from the small disc 15 to serve as abutments for detent projecting springs 20 bent in the general shape of a bow with the reentrant ends of the spring engaging detents 21 which are guided in radial channels 22 formed in the surface of the disc 15. The detents 21 have semispherical heads adapted to frictionally engage in the indentations 12 in the rim of the larger disc 10. This construction insures the maximum leverage for the frictional surfaces and thereby permits the use of lighter springs 21 and a smoother movement of the glass frame from one position to the other as the detents need not engage so deeply in the indentations in the rim of the larger disc as has been necessary with the prior art structures.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

A windshield hinge comprising a disc 90 having a flanged rim with a series of indentations therein, a second disc adapted to fit within the flange of said first disc, a pivot bolt, lugs struck from said second disc adapted to serve as spring abutments, radial detent guides formed on the surface of said second disc, detents therein adapted to engage in the indentations of the first disc and springs engaged between said detents and said lugs to force said detents outwardly.

In testimony whereof I have hereunto subscribed my name.

GEORGE A. JACOBS.
